UNITED STATES PATENT OFFICE.

HOMER E. BRIDGE, OF HAZARDVILLE, CONNECTICUT.

ROTARY STEAM-ENGINE.

SPECIFICATION forming part of Letters Patent No. 735,203, dated August 4, 1903.

Application filed December 23, 1902. Serial No. 136,359. (No model.)

To all whom it may concern:

Be it known that I, HOMER E. BRIDGE, a citizen of the United States of America, and a resident of Hazardville, in the county of Hartford and State of Connecticut, have invented certain new and useful Improvements in Rotary Steam-Engines, of which the following is a full, clear, and exact description.

This invention relates to improvements in engines, more particularly steam-engines of a class wherein the piston has a continuous revoluble motion within an annular steam-chamber, such piston having attachment to a central shaft or body, by which it is carried and from which it extends radially into and to closely fit the walls of the aforesaid annular steam-chamber, a part termed a "rotary abutment" serving to constitute the end wall for the steam-space, the other end wall of which is constituted by the movable revoluble piston, provisions for the control and conveyance of the pressure and exhaust-steam being made.

The objects of the invention are to provide a generally-improved organization of the parts and appliances which constitute the engine for acquiring a high degree of efficiency, for enabling the steam to be used expansively, if desired, or to be used at high pressure entirely or changed instantly, so as to run partially under the impact of the steam and partially under the expansive action thereof, with capability for varying the time in each cycle in which the engine will run under expansion and for insuring capabilities of reversal of the engine.

The invention consists in the construction and co-operative arrangement or combination of parts, all substantially as hereinafter fully described in connection with the accompanying drawings and set forth in the claims.

In the accompanying drawings, Figure 1 is substantially a sectional view taken through the engine transversely of the driving-shaft thereof. Fig. 2 is a horizontal sectional view on line 2 2, Fig. 1. Fig. 3 is an elevation of the engine as seen at the opposite or rear side of the sectional elevation, Fig. 1. Fig. 4 is a vertical sectional view as taken on the line 4 4, Fig. 2, and looking in the direction of the arrow. Fig. 4^a is a sectional view showing a slight modification in one of the appliances

different from the corresponding part shown in Fig. 4. Figs. 5, 6, and 7 are perspective views of portions of the apparatus to be hereinafter particularly referred to.

Similar characters of reference indicate corresponding parts in all of the views.

The engine or motor comprises a body constructed in the form of a casing A, having the annular chamber a therein corresponding to the cylinder of an engine, such annular chamber a opening at b into a chamber B, of cylindrical form, the axis of which is parallel with the axis of the annular chamber a and the casing to form and inclose the said annular chamber a, and the cylindrical chamber B is constructed of the two separate castings 10 and 12, arranged facewise the one against the other and confined by the plurality of bolts d with nuts and screws d'.

The casing-sections 10 12 are constructed with intermediate opposite hubs 13 13 to constitute journal-bearings for the main shaft C of the engine, on which is keyed or otherwise affixed a disk or comparatively large circular plate D facewise closely next to the inner surfaces of the casing-sections 10 and 12, but rotatable relatively thereto in unison with the main shaft, and this disk has the radially and edgewise extended piston in the form of a circular disk D to closely fit and move around without steam leakage in the annular chamber a of the engine-casing, the axis of this piston-disk being coincident with the central circular line or what may be regarded as the circular axis of the said steam-chamber a. This piston-disk is constructed in the form of two separate sections, having a shank portion e fitted and confined in a dovetail-shaped aperture therefor in the disk D, the radial projecting portions being clamped together by the bolts and nuts e', confining annular packings e² in rabbets formed within their inner surfaces.

E represents the rotary abutment of a general cylindrical form, having opposite end walls 15 15 and a plurality, here three, of semi-cylindrical recesses 16, opening to the periphery of the said appliance E, so as to permit in proper time the accommodation of the radial piston therethrough as such piston is moving in its circular path, the solid portion of the abutment constituting properly an end

wall to the annular steam-chamber α , as readily understood. The said rotary abutment has an axial length slightly less than the axial length of the aforementioned chamber 5 B, so that at one end of the rotary abutment and between such end and the adjacent end wall of the chamber B is fitted a valve-disk F, the same having a sleeve F^2 , which loosely fits over the counter-shaft G, on which the 10 aforementioned rotary abutment E is connected or otherwise affixed, rear bearings at 17 17 being provided for the main shaft C and counter-shaft G, which may be properly termed the "abutment-shaft." The one end 15 wall of the rotary abutment has the ports f therethrough, being three or other number, corresponding to the number of the semicylindrical openings 16, these ports being of such length relatively to the circle of rotation of 20 the rotary abutment as to receive the ample steam-supply as permitted to pass therethrough by the ports of the valve-disk F.

The ports of the valve-disk F are shown as three in number, those, g g , being inlet-ports, 25 while the one, h , is the exhaust-port. Through the end wall of the cylindrical chamber B, adjoining which is the valve-disk F, are oppositely-located inlet and opposite ports i and j , having communication, respectively, 30 with the steam-supply pipe H and the exhaust-pipe J by way of the opposite (upper and lower) passages H' and J' .

The sleeve F^2 , on which the valve-disk F is mounted, has affixed thereto a radially-expanded lever-arm F^3 , by means of which the disk may be rotated in any desired slight extent to regulate the lead and cut-off which is acquired by the registry of the ports G with the ports F through the end wall of the rotary abutment leading to the steam-space 16 therein connected with the annular steam-chamber of the engine, and said valve-disk is provided to have a further function of a reversing appliance for the engine. The passages H' and J' are extended between the aforementioned ports i and j and the cylindrical chamber K, in which is fitted a valve-plug L, such plug, of the form shown in Fig. 4, being a three-way plug and having an axial 40 passage 20, continued in a radial passage 22, extending to its periphery.

The passage or branch 23 of the valve-plug L is adapted to register with the inlet steam-supply passage H, which enters 55 through the side of the portion of the casing, within which the chamber K is inclosed, and one of the branches 24 in continuation of the branch 23 has a crosswise course to lead, for instance, to the steam-passage H' , the other 60 crosswise branch 25 terminating against the closed inner portion of the casing-wall, and when the branch 24 is in connection between the steam-inlet H and the passage H' the axial passage 20 and its radial continuation 22 65 have communication with the exhaust-passage J' , it being seen in Figs. 2 and 3 in what manner the exhaust or waste conduit J has

connection with the central passage through the valve-plug and end wall of the casing within which said plug is inclosed. The said 70 valve-plug L has the axial stem k , on which is a handle-lever K^2 , by means of which partial rotary motion may be imparted to the plug.

There is affixed upon the counter-shaft G 75 a disk M, having a set of deep notches m therein in number corresponding to the semicylindrical openings 16 in the rotary abutment E and producing separate radial engagement members for the abutment-shaft, and mounted upon a disk or rotatable support N on the driving-shaft is a stud p , Fig. 3, which once every revolution thereof in unison with each turn of the main shaft engages in one of the notches m of said disk, remaining in engagement just long enough to carry the disk M around one-third of a turn, thereby turning the shaft G correspondingly to rotate the rotary abutment E a third way around in proper time to let the radial passage D pass 85 the adjacent partition between two of the openings in the abutment and to bring another port f in the end wall of the rotary abutment into registry with the one, g , of the ports through the valve-disk F which gives 90 communication with the steam-supply therethrough.

It is desirable to employ a click or detent in conjunction with the toothed disk M, and a form of such a device as indicated in Fig. 100 3 at L, consisting of a roller 30 on the end of a pivotally-mounted lever 32, a spring 33 keeping the lever up to the proper presentation with the roll against the notched edge of the disk. Any other approved form of detent or functional device may be used. In addition to the deep notches m in the disk M there are intermediate less deep notches n , co-operating with which is an adjustable stud q , carried on the rotary support N. This 105 stud q is affixed to an arc-shaped plate Q, which has slots q' , through which confining bolts or screws q^2 are passed with a screw engagement into the rotary support N, the enlarged heads of these screws clamping the 110 plate Q in its given position of adjustment. The stud q is adjustable radially in the slot r , formed in the plate Q, so that it may have a position for impingement in one of the notches of the disk M, which may be located 115 adjacent its circular path, the depth of the engagement of this stud into the notched part and the corresponding length of the impingement being regulated by the extent to which the stud is adjusted inwardly on the support 120 N, and the instant of its impingement may be rendered slightly earlier or later in its every revolution by sliding the plate around in one direction or the other on the circular support N.

Now in the operation of the engine with parts adjusted about as shown in the drawings it will be perceived that the piston D will rotate in the direction of the arrow x be-

cause of the ingress of steam through the rotary abutment-port *f* coming therethrough to the narrow port *g* in the valve-disk *F*, which is in communication with the steam-5 inlet passage *H'*, and the steam under pressure will drive the piston around in the direction of the aforesaid arrow, and it will be understood that the aforementioned adjustable stud *q* will when the piston *D* has made 10 one-half of a revolution, more or less, under the impact of the steam come to impingement against the pathway of one of the notches of the disk *M*, remaining in such impingement just long enough to force the rotary abutment 15 *E* around in the direction of the arrow sufficiently to carry the abutment-port *f* completely out of registry with the port *g*, thereby cutting off the steam and leaving the engine to work for the latter half of the revolution 20 of the piston *D* under the expansion of the steam, and as the piston approaches the partition of the rotary abutment which is across the steam-chamber *a* the aforementioned stud *p*, having the comparatively deep 25 impingement within the disk-notch adjacent its path, will cause the rotation of the disk-shaft *G* and rotary abutment one-third of a turn to let the abutment-partition across the steam-chamber assume the out-of-the-way position, 30 allowing the piston to pass in the opening 16 and the ports *f* to come adjacent and into registry with the steam-inlet port *g*, and of course it will be understood that so soon as the piston comes to the completion of its cycle 35 the steam may exhaust through the rotary abutment-port *f*, through which the steam was taken, the exhaust being carried through the long port *h* in the valve-disk and therefrom through the exhaust-passage *J'* and passages 22 and 20 to the exhaust-conduit *J*. Of course by adjusting the said stud *q* the cutting off of the steam into the steam-chamber may be very early in the cycle of the piston 40 or very late therein, or there may be no cutting off, the complete revolution of the piston in the latter case being under the pressure or impact of the steam. To reverse the engine, the lever *K*² is swung from the position shown in full lines, Fig. 3, to that shown 45 in dotted lines. The steam thereupon instead of going by the passages 24 and *H'* goes by the passage 24 to and through the passage *J'*, and in proper season the disk valve has a reversal of its position given thereto by 50 swinging the lever *F*, so that the long port *H* therein will take the position relatively to the upper left-hand port *g* of Fig. 1, while the one of the narrow ports *g* will come into 55 registry with the lower abutment-port *f*, in consequence of which of course the steam ingress into the steam-chamber *a* is in the reversed direction from that shown by the arrow *x* to result in a corresponding reversed driving of the piston and the main shaft. 60 The engine may be throttled by turning in the proper extent the plug-valve *K* or by turning in the proper extent the valve-disk *F*.

In the drawings, Fig. 4^a, the valve-plug *L* is shown as having the single way 24 and the axial and radial passages 20 and 22, by means 70 of which the reversal of the engine may be accomplished in the manner above described substantially; but to bring the valve so that the passages therein have the arrangement for reversing which is indicated by the dotted 75 lines in Fig. 4^a considerably greater extent of rotary motion has to be given to the said valve.

It is to be stated that this engine apparatus is susceptible of considerable modification 80 and change in respect of details of construction without departing from the leading characteristics of my invention, and while in the foregoing description the engine has been referred to generally as a steam-engine it is 85 not limited to the use of steam, for it may be run by gas, explosively used or otherwise employed, or by air, water, or other fluid or motor agent.

In respect of the valve-disk *F*, shown and 90 described as a component in this engine, it is to be stated that this is a comparatively important and valuable appliance in its coöperative relations in the engine to the steam and exhaust ports *i* and *j* adjacent the cylindrical chamber *B* and to the end port-provided wall of the rotary abutment *E*, contributing, as it does, to the controlling and varying capabilities; but this device may be considered in one sense as a movable layer 95 or section of the wall of the chamber *B*, having openings which may variably register with or be thrown out of coincidence with the ports of the steam-conduit as desired, and a simple form of the engine may be constructed 100 wherein this valve-disk *F* may be omitted, in which case of course the end wall of the rotary abutment would be disposed closely against the end wall of the chamber *B*, through 105 which are the ports *i* and *j*.

Having thus described my invention, what I claim, and desire to secure by Letters Patent, is—

1. In a rotary steam or other engine, in combination, a casing having an annular steam-chamber and an adjoining approximately cylindrical chamber communicating therewith, and a rotatable carrier having a radial piston fitting and revolvable in the steam-chamber, said casing having inlet and exhaust ports 115 through the end wall of the said cylindrical chamber, a rotary abutment of cylindrical form having a plurality of recesses opening to its periphery and having an end wall adjacent said port-provided wall of the casing, 120 which abutment-wall has ports respectively leading therethrough into the peripherally-opening recesses therein, and means for periodically partially rotating said rotary abutment.

2. In a rotary steam or other engine, in combination, a casing having an annular steam-chamber and an adjoining approximately cylindrical chamber communicating therewith,

and a rotatable carrier having a radial piston fitting and revoluble in the steam-chamber, said casing having inlet and exhaust ports through the end wall of the said cylindrical chamber, a steam-inlet conduit and a steam-exhaust conduit, and a chamber with which they communicate having a steam-valve fitted therein, and passages leading from different portions of the latter chamber respectively to said inlet and exhaust ports, a rotary abutment of cylindrical form having a plurality of recesses opening to its periphery and having an end wall adjacent said port-provided wall of the casing, which abutment-wall has ports respectively leading therethrough into the peripherally-opening recesses therein, and means for periodically partially rotating said rotary abutment.

3. In a rotary steam or other engine, in combination, a casing having an annular steam-chamber and an adjoining approximately cylindrical chamber communicating therewith, and a rotatable carrier having a radial piston fitting and revoluble in the steam-chamber, said casing having inlet and exhaust ports through the end wall of the said cylindrical chamber, a rotary abutment of cylindrical form having a plurality of recesses opening to its periphery and having an end wall adjacent said port-provided wall of the casing, which abutment-wall has ports respectively leading therethrough into the peripherally-opening recesses therein, and a shaft provided to the rotary abutment having a disk with a plurality of notches therein, and a rotary support connected to the piston to turn in unison therewith having a stud adapted for periodical impingement against said notched disk.

4. In a rotary steam-engine, in combination, a casing having an annular steam-chamber and an adjoining approximately cylindrical chamber communicating therewith, and a rotatable carrier having a radial piston fitting and revoluble in the steam-chamber, said casing having inlet and exhaust ports through the end wall of the said cylindrical chamber, a rotary abutment of cylindrical form having a plurality of recesses opening to its periphery and having an end wall adjacent said port-provided wall of the casing, which abutment-wall has ports respectively leading therethrough into the peripherally-opening recesses therein, a shaft extended from the rotary abutment having a disk thereon provided with the notches, an externally-located rotary support connected to the piston, to turn in unison therewith, having a stud adapted for periodical impingement against the notched disk and a detent device engaging the notched disk.

5. In a rotary steam or other engine, in combination, a casing having an annular steam-chamber and an adjoining approximately cylindrical chamber communicating therewith, and a rotatable carrier having a radial piston fitting and revoluble in the steam-chamber, said casing having inlet and exhaust ports

through the end wall of the said cylindrical chamber, a rotary abutment of cylindrical form having a plurality of recesses opening to its periphery and having an end wall adjacent said port-provided wall of the casing, which abutment-wall has ports respectively leading therethrough into the peripherally-opening recesses therein, means for periodically partially rotating said rotary abutment to bring its respective ports into registry with the inlet and exhaust ports, and means for imparting slight supplemental rotational movements to the rotary abutment subsequent to each operation of said abutment-rotating means, for the purposes set forth.

6. In a rotary steam or other engine, in combination, a casing having an annular steam-chamber and an adjoining approximately cylindrical chamber communicating therewith, a rotatable carrier having a radial piston fitting and revoluble in the steam-chamber, and said casing having inlet and exhaust ports through the end wall of the said cylindrical chamber, a rotary abutment of cylindrical form having a plurality of recesses opening to its periphery and having an end wall adjacent said port-provided wall of the casing, which abutment-wall has ports respectively leading therethrough into the peripherally-opening recesses therein, means for periodically partially rotating said rotary abutment to bring its respective ports into registry with the inlet and exhaust ports, the shaft extended from the abutment having the disk M provided with series of peripheral notches, the rotary carrier N movable in unison with the revoluble piston having the stud p and the secondary stud q arranged for successive operations in the notched disk M for the purposes set forth.

7. In a rotary steam or other engine, in combination, a casing having an annular steam-chamber and an adjoining approximately cylindrical chamber communicating therewith, and a rotatable carrier having a radial piston fitting and revoluble in the steam-chamber, said casing having inlet and exhaust ports through the end wall of the said cylindrical chamber, a rotary abutment of cylindrical form having a plurality of recesses opening to its periphery and having an end wall adjacent said port-provided wall of the casing, which abutment end wall has ports respectively leading therethrough into the peripherally-opening recesses in the abutment, the abutment-shaft having a part thereon provided with a plurality of separated radially-extended engagement members, the carrier N having the stud p and the secondary stud q adjustable radially thereon for the purposes set forth.

8. In a rotary steam or other engine, in combination, a casing having an annular steam-chamber and an adjoining approximately cylindrical chamber communicating therewith, and a rotatable carrier having a radial piston fitting and revoluble in the steam-chamber,

said casing having inlet and exhaust ports through the end wall of the said cylindrical chamber, a rotary abutment of cylindrical form having a plurality of recesses opening 5 to its periphery and having an end wall adjacent said port-provided wall of the casing, which abutment end wall has ports respectively leading therethrough into the peripherally-opening recesses in the abutment, the 10 abutment-shaft having a part thereon provided with a plurality of separated radially-extended engagement members, the carrier N having the stud p and the secondary stud q adjustable radially thereon, said stud being also adjustable in a line around said carrier, for the purposes set forth.

9. In a rotary steam or other engine, in combination, a casing having an annular steam-chamber and an adjoining approximately cylindrical chamber communicating therewith, and a rotatable carrier having a radial piston fitting and revoluble in the steam-chamber, said casing having inlet and exhaust ports through the end wall of the said cylindrical 25 chamber, a rotary abutment of cylindrical form having a plurality of recesses opening to its periphery and having an end wall adjacent said port-provided wall of the casing, which abutment-wall has ports respectively 30 leading therethrough into the peripherally-opening recesses therein, the abutment-shaft having the deep notches dividing it into separate radial engagement members, and the carrier N pertaining to the piston having the engagement-stud p and having a plate Q adjustable in an arc line around on said carrier, and provided with the stud q which is adjustable on the said adjustable plate in a line radially relatively to said carrier.

40 10. In a rotary engine, in combination, the casing having the annular steam-chamber and an approximately cylindrical chamber communicating with the annular chamber, and having separated inlet and exhaust ports leading 45 through the end wall of the cylindrical chamber, a rotatable shaft and a radial piston-wing fitting and movable around in the annular chamber, the rotary abutment having a plurality of recesses therein opening to the 50 periphery thereof fitted in said cylindrical chamber, the valve-disk F, having narrow separated inlet-ports and a comparatively long exhaust-port, located between the end of the rotary abutment and the aforesaid port- 55 provided end wall of the cylindrical chamber, means for rotatably adjusting said valve-disk, and means for imparting periodical rotational movements to the rotary abutment.

11. In a rotary engine, in combination, the 60 casing having the annular steam-chamber and an approximately cylindrical chamber communicating with the annular chamber, and having separated inlet and exhaust ports leading 65 through the end wall of the cylindrical chamber, a rotatable shaft and a radial piston-wing fitting and movable around in the annular chamber, the rotary abutment having

a plurality of recesses therein opening to the periphery thereof, and having a circular end wall provided with ports opening therethrough into the said recess, said abutment being fitted in said cylindrical chamber, the valve-disk F, having narrow separated inlet-ports and a comparatively long exhaust-port, located between the port-provided end wall 70 of the rotary abutment and the aforesaid port-provided end wall of the cylindrical chamber, means for rotatably adjusting said valve-disk, and means for imparting periodical rotational movements to the rotary abutment. 75

12. In a rotary engine, in combination, the casing having the annular steam-chamber and an approximately cylindrical chamber communicating with the annular chamber, and having separated inlet and exhaust ports leading 80 through the end wall of the cylindrical chamber, a rotatable shaft carrying a radial piston-wing, fitting and movable around in the annular chamber, the rotary abutment having a plurality of recesses therein opening 85 to the periphery thereof fitted in said cylindrical chamber, and having an externally-projected shaft, the valve-disk F, and a sleeve on which it is mounted, said disk having narrow separated inlet-ports and a comparatively 90 long exhaust-port, and located between the end of the rotary abutment and the aforesaid port - provided end wall of the cylindrical chamber, its said sleeve surrounding the abutment-shaft, means connected with said sleeve 95 for turning it and the disk carried thereon, and means for imparting periodical rotational movements to the rotary abutment-shaft. 100

13. In a rotary engine in combination, the casing having the annular steam-chamber and 105 an approximately cylindrical chamber communicating with the annular chamber, and having separated inlet and exhaust ports leading through the end wall of the cylindrical chamber, a rotatable main shaft and a radial 110 piston-wing fitting and movable around in the annular chamber, the rotary abutment having a plurality of recesses therein opening to the periphery thereof fitted in said cylindrical chamber, and having a shaft provided with the disk M having separated engagement members, the valve-disk F, having narrow separated inlet-ports and a comparatively long exhaust-port, located between the end of the rotary abutment and the aforesaid 115 port - provided end wall of the cylindrical chamber, and having a sleeve surrounding the abutment-shaft which is provided with the lever F, and the rotary carrier on the main shaft having a revoluble member thereon to impinge periodically and successively 120 against the said engagement members of said disk. 125

14. In a rotary steam-engine, in combination, the engine-casing having the annular 130 steam-chamber a and the approximately cylindrical chamber B communicating with the steam-chamber, the main shaft and the radial revoluble piston, said casing having inlet and

exhaust ports *i* and *j* leading through the end wall of said cylindrical chamber *B*, a cylindrical valve-chamber *K* having radial steam-inlet conduit *H* and axial steam-exhaust conduit *J*, with the passages *H'* and *J'* extending from connection with the chamber *K* respectively to the ports *i* and *j*, the rotary abutment *E* fitted and rotatable in the said chamber *B* and having recesses therein opening to the periphery thereof, a valve-plug having a transverse steamway therethrough and an exhaust-passage extending axially thereinto and continued radially to the periphery of the valve, means for turning said valve and means for periodically imparting rotational movements to the rotary abutment.

15. In a rotary steam-engine, in combination, the engine-casing having the annular steam-chamber *a* and the approximately cylindrical chamber *B* communicating with the steam-chamber and the main shaft and the radial revoluble piston, and said casing having inlet and exhaust ports *i* and *j* leading through the end wall of said cylindrical cham-

ber, a cylindrical valve-chamber *K* having radial steam-inlet conduit *H* and axial steam-exhaust conduit *J* with the passages *H'* and *J'* extending from connection with the chamber *K* respectively to the ports *i* and *j*, the rotary abutment *E* fitted and rotatable in the said chamber *B* having the circular end wall provided with the ports *f f*, and having the recesses *16* therein opening to the periphery thereof, the valve-disk *I* having the ports *g g* and *h*, a valve-plug *L* having a transverse steamway therethrough and an exhaust-passage extending axially thereinto and continued radially to the periphery of the valve, a lever for turning said valve-plug *L*, a lever for turning said valve-disk *F*, and means for periodically imparting rotational movements to the rotary abutment.

Signed by me at Springfield, Massachusetts, in presence of two subscribing witnesses.
